Atty.

A. HAMILTON BALLAGH, OF WESTPORT, MISSOURI.

Letters Patent No. 87,819, dated March 16, 1869.

IMPROVEMENT IN HARROWS.

The Schedule referred to in these Letters Patent and making part of the same.

To all whom it may concern:

Be it known that I, A. HAMILTON BALLAGH, of Westport, in the county of Jackson, and State of Missouri, have invented a new and improved Harrow; and I do hereby declare that the following is a full, clear, and exact description thereof, which will enable others skilled in the art to make and use the same, reference being had to the accompanying drawings, forming part of this specification, in which—

Figure 1 is a plan view of my improved harrow.

Figure 2 is a sectional view of the same, the line being taken through the line $x x$, fig. 1.

Similar letters of reference indicate corresponding parts.

The object of this invention is to provide a simple and effective harrow, of that class in which the lateral beams may be shifted, so as to bring the teeth from a vertical to a horizontal position, or *vice versa*; and

It consists in the combination of devices, as herein-after stated.

A A B is the frame, braced by a stay-rod, E, and provided with a number of oscillating cross-beams, C, which bear the harrow-teeth a .

The trunnion-ends g of the cross-beams are afforded bearings, in the sides A A of the frame, as shown.

D is a connecting-beam, which is arranged on top of the part B of the frame, and the cross-beams, and is connected with the latter by means of crank-irons f .

One part of each crank-iron works loosely in the connecting-beam, and the other corresponding part works loosely in an eye in one of the adjacent teeth, the end of which latter projects sufficiently above its respective beam to afford the proper connection.

By moving this connecting-beam to and fro, the oscillating cross-beams will be brought to present the harrow-teeth vertically or horizontally, as shown at fig. 2.

When the teeth are vertical, the cross-beams are held firmly in this position, by means of a catch-bolt, e, which works in a mortise in the beam D.

The lower end of this catch-bolt is bevelled, so that it will pass over the part B of the frame, when the teeth are to be brought from a horizontal position to a vertical position.

The catch-bolt contains a coiled spring within a recess, which exerts its force to push down the bolt, after it has passed the rear edge of the part B, and thus act as a stop, to prevent the teeth from yielding to the resistance of the soil, when the harrow is drawn forward.

The coiled spring in the catch-bolt acts against a rod passing through the mortise in the beam D, and the recess in the catch-bolt, thereby causing the force of the spring to actuate the catch-bolt downward.

The beam D is connected, at its rear end, with a hand-lever, G, by an eye-bolt, h, and plate i, the former being affixed in the lever, and the latter bolted to the beam D, and the link and plate connected as shown.

The lower end of the lever rests against the rounded

edge of the rear cross-beam, which thus affords a fulcrum for the lever, in operating the cross-beams.

This lever is connected with the said rear cross-beam in any loose manner that will permit its movement.

The catch-bolt is withdrawn into the mortise when the teeth are to be thrown back horizontally, by means of a bell-crank, d, (which is pivoted to the catch-bolt, and to a lug-plate, or other equivalent device on the beam D,) a rod, b, and a supplemental lever, H.

The rod connects the bell-crank with the lever, which latter is pivoted to the lever G, as shown.

I is the iron to which the beam is attached.

The front end of the beam D rides in a deep rectangular notch in the part B of the frame, which notch thus serves as a guide for the beam.

This notch is further formed with lateral channels at its base, in which the lateral strips k, affixed to the beam D, slide freely.

This device serves to hold the beam from being raised by the resistance of the soil, when the teeth are being brought to the vertical position.

It will thus be seen that the teeth of the harrow may, by the operation of the lever G, be brought to a vertical position, cultivating the soil, and thrown forward again, when the teeth become choked up with trash, by simply pulling back the supplemental lever H, which draws the lower end of the catch-bolt entirely within the mortise in which the bolt works, thus allowing the beam D to move forward, in obedience to the resistance of the soil to the teeth as the harrow moves forward.

This harrow, from its facility of operation, can be managed by a single attendant with ease, as no lifting of the harrow is required in passing obstructions or turning, as in these latter operations, it is only required to throw back the teeth in the manner described, as will be obvious.

The red outlines, in fig. 2, illustrate the position of the movable parts when the teeth are thrown back.

Having thus described my invention,

I claim as new, and desire to secure by Letters Patent—

1. The combination, in a harrow, of the frame A A B, beam D, oscillating toothed beams C, crank-irons f , and lever G, substantially as and for the purpose herein shown and described.

2. The combination, with the above-claimed parts, of the catch-bolt e, operating substantially as and for the purpose shown and described.

3. The combination, with the parts A, A, B, C, D, f, and G, of the catch-bolt e, rod b, and lever H, substantially as and for the purpose herein shown and described.

A. H. BALLAGH.
